DESIGN FOR A TOASTER OR THE LIKE

Arban J. Ackerman, New York, N. Y., assignor to Manning, Bowman & Co., Meriden, Conn., a corporation of Delaware

Application September 17, 1935, Serial No. 58,583

Term of patent 7 years

To all whom it may concern:

Be it known that I, Arban J. Ackerman, a citizen of the United States, residing at New York city, county and State of New York, have invented a new, original, and ornamental Design for a Toaster or the like, of which the following is a specification, reference being had to the accompanying drawing, forming a part thereof.

Fig. 1 is a perspective view of a toaster, showing my new design; and

Fig. 2 is an end view thereof on a slightly reduced scale.

I claim:

The ornamental design for a toaster or the like, substantially as shown and described.

ARBAN J. ACKERMAN.
